UNITED STATES PATENT OFFICE.

WILLIAM W. HUSTON, OF EAGLE GROVE, IOWA.

EMERGENCY-CHAIN FOR CARS.

1,184,241.

Specification of Letters Patent. Patented May 23, 1916.

Application filed September 3, 1915. Serial No. 48,888.

To all whom it may concern:

Be it known that I, WILLIAM W. HUSTON, a citizen of the United States, residing at Eagle Grove, in the county of Wright and 5 State of Iowa, have invented certain new and useful Improvements in Emergency-Chains for Cars, of which the following is a specification:

My invention relates to new and useful 10 improvements in emergency chains for handling cars. Heretofore, chains for this purpose have been formed in a single length and to stand the strain and serve the purpose for which they are intended must be so heavy and unwieldy that they can be applied only by two or more men. As these 15 chains are commonly employed to connect adjacent freight cars, in case the draw bar, ordinarily connecting the cars, has pulled 20 out, they have been unsatisfactory. This is largely due to the fact that, under such circumstances, the majority of the train crew have to be sent to the front and rear of the train to signal any possible trains approaching and a sufficient number of men for the 25 purpose of chaining the cars together is not always available.

The primary object of my invention consists in the provision of an emergency chain 30 formed in two parts, each of which may be readily coupled to the axle of a car and to the other.

In this connection, a still further object 35 of my invention consists in providing each chain, at one end, with an attaching member including a pair of pivoted jaws arranged, when closed, to form a ring for engagement about the car axle and at its other end a chain link engaging grab hook, the chain 40 being so secured to the attaching member that when subjected to strain, the jaws of such member will be swung to closed position and cannot be opened until the strain is released.

45 A still further object of my invention consists in providing a structure of the above described character which is simple, readily assembled and readily taken apart in case of necessity for repairs, due to 50 breakage.

With these and other objects in view, my invention will be more fully described, illustrated in the accompanying drawings, and then specifically pointed out in the claims

which are attached to and form a part of 55 this application.

In the drawings: Figure 1 is a fragmentary sectional view of the adjacent ends of two freight cars, showing my emergency chain in use, the chain being shown in elevation; Fig. 2 is a perspective view of one of the members making up my two part emergency chain; Fig. 3 is a side elevation of one of the attaching members, the position of its swinging jaw, when in open position, 60 being shown in dotted lines; Fig. 4 is a transverse vertical section taken on the line 4-4 of Fig. 3, looking in the direction of the arrows; Fig. 5 is a fragmentary longitudinal section taken on the line 5-5 of 70 Fig. 4.

Corresponding and like parts are referred to in the following description and indicated in all the views of the drawings by the same reference characters.

The preferred embodiment of my invention, as illustrated in the drawings, includes a pair of chain members, each indicated as a whole by the numeral 10 and each including an attaching member 11, chain 12 and 80 grab hook 13. As both of the chain members 10 are identical in construction, a description of one will suffice for both.

Referring more particularly to Figs. 2 to 5 of the drawings, it will be seen that the 85 attaching member 11 includes a shank portion 14 terminating at one end in a downwardly curved jaw 15 and adjacent its other end and upon its upper face with an upstanding lug or extension 16. The shank, 90 adjacent the jaw, is also provided with an upstanding bearing shoulder 17, the upper face of which is concave transversely, as shown at 18, for a reason which will be later apparent. The attaching member further 95 includes a pivoted jaw 19, the body portion 20 of which is reduced in thickness to seat in a recess formed by correspondingly reducing the shank and jaw portion of the body of the attaching member, as shown at 21 in 100 Fig. 5. This swinging jaw 19 is pivoted to the shank of the attaching member by a pivot pin or bolt 22 which is perforated to receive a split pin 23 by means of which a nut 24 threaded upon its shank may be 105 locked in place. It is obvious that in place of threading the shank of this bolt or pin and employing a nut, the shank may be left

unthreaded and a washer employed instead. Preferably, the jaws 15 and 19 are so shaped that when closed they form a ring proportioned to engage relatively snugly about the 5 axle of a car and the free end of the jaw 15 is preferably formed with a longitudinal notch 25 to receive a longitudinal rib or shoulder 26 formed upon the free end of the other jaw when the jaws are brought together. This interlocking rib and shoulder 10 prevents any likelihood of independent lateral movement of the jaws under strain and, consequently, relieves the pivot pin or bolt 22 of considerable strain.

15 The rear end of the body portion 20 of the swinging jaw 19 is formed with an up-standing extension 27 corresponding to the extension 16 of the shank of the other jaw but located at a somewhat higher lever and 20 both of these extensions are formed with bores 28 extending parallel to the axis of the shank of the attaching member when the device is in use. A pin 29 is passed through the bore of the extension 27 and 25 is locked against movement toward the extension 16 by a split pin 30 which retains a nut or washer 31, as the case may be. The opposite end of this pin 29 is provided with an enlarged head 32 having an opening to 30 receive a ring 33 and one end of the chain 12 is passed through the bore 28 of the extension 16 and attached by one terminal link to the eye 33. The terminal link at 35 the end of the chain is attached to a corresponding ring 34 which is passed through the eye 35 of the grab hook 13 and the bill portion of this hook, as clearly shown in the drawings, is so arranged and proportioned that the hook may be made to straddle any link of the chain and prevent slipping of the chain through the hook.

40 To insure a clear and accurate understanding of my invention and its use, I have illustrated it as employed in connecting two freight cars 36 which have become uncoupled due to the pulling out of their draw bar. When so employed, the attaching members are connected to the axles 37 at adjacent ends of the cars 36 and the free 45 ends of the chains secured to each other by means of the grab hooks 13, as clearly shown in Fig. 1. In applying the chain in this manner, each chain is separately applied, the chain 12 of each attaching member being drawn forwardly through the extension 16 a sufficient distance to permit the downward swinging of the pivoted jaw 19 to the position shown in dotted lines in Fig. 3.

50 The attaching member is then grasped by the free end of its shank 14 and extended beneath the car until its jaw 15 is hooked over the axle 37 when strain is exerted upon the chain 12 to swing the jaw 19 into engagement with the jaw 15 and so connect 55 the attaching member to the axle. When

60 65

both attaching members have been thus connected to the axles of the cars to be joined, the free ends of the chains 12 are brought together and connected in any suitable manner by one or both of the grab hooks 13.

As will be seen by reference to Fig. 1 of the drawings, the shanks of the attaching members are of such length that the person applying them need not crawl under the car and is therefore, to a great extent, protected from any likelihood of injury which might otherwise result should either of the cars start as the entire operation of connecting the cars can be done by a man standing between them. The chains proper, 12 are necessarily of such weight that when drawn to move the jaws into engagement with each other they will continue to hold the jaws in such engagement until manually loosened. For this reason, one man may 80 first attach one of the chains to one axle and then the other chain to the other axle and then connect the free ends of the chains. By locating the extension 27 somewhat above the level of the extension 16, the chain 90 exerts a greater strain upon the jaw 19, tending to hold it in engagement with the jaw 15 and tend to tilt the free end of the shank of the attaching member upwardly somewhat in order that the upper jaw 15 95 may be the jaw taking up the greater portion of the strain instead of having the strain applied to the extreme ends of the jaws. This extension 27 also, due to its abutment against the shoulder 17, serves as 100 a means for limiting the swinging of the jaw 19 toward the jaw 15 and therefore prevents any likelihood of bending such jaw out of shape under undue closing strain. The grooved upper face 18 of the shoulder 17 permits turning of the pin 29 when the device is in use and these pins may, therefore, swivel in their bearings to permit 105 proper manipulation of the chains 12.

Although I have illustrated and described the emergency chain as employed for coupling freight cars, it will of course be understood that it is capable of a wide range of use for other purposes, particularly in machine shops and switch yards and that I do not wish to be limited either to its use or to the specific details of construction described.

Having thus described the invention, what is claimed as new is:

1. An emergency chain including an attaching member having pivotally connected jaws adapted to engage about an axle, a flexible draft element connected to the attaching member and adapted to co-act with the jaws to hold them together, and a hook carried by the free end of the draft element.
2. An emergency chain for coupling cars including a pair of axle engaging members, each axle engaging member including a shank terminating at one end in a curved 130

jaw, a second curved jaw pivotally connected to the shank and coöperating with the first to engage about an axle, a sleeve formed upon the free end of the shank, and chains provided at one end with hooks and at the other ends passed through the sleeves and secured to the bodies of the pivoted jaws.

3. An emergency chain for coupling cars including a pair of axle engaging members 10 comprising pivotally connected jaws adapted to engage about an axle, chains connected to one of the jaws, hooks carried by the free ends of the chains, and means co-acting between the chains and other jaws, whereby 15 strain upon the chains will hold the jaws in closed position.

4. An emergency chain including an attaching member having an elongated shank terminating at one end in a sleeve and at 20 the other in a jaw, a second jaw pivotally connected to the shank adjacent the first jaw and adapted therewith to form an eye when in closed position, a chain connected to the body of the second jaw and extended 25 through the sleeve, and chain engaging means carried by the end of the chain.

5. An emergency chain including pivotally connected jaws adapted in closed position to provide a closed ring, an upwardly 30 directed shank extending from one jaw, a

laterally directed elongated shank extending from the other jaw, sleeves formed upon the free end of the second shank and upon the free end of the first shank, a retaining member swivelly mounted in the second 35 sleeve, a chain passed through the first sleeve and connected to the retaining member, and chain engaging means connected to the chain.

6. An emergency device for coupling cars 40 including a pair of axle engaging members, each axle engaging member including a shank terminating at one end in a curved jaw, a second curved jaw pivotally connected to the shank and coöperating with the 45 first to engage about an axle, and means connected to the axle engaging members and adapted for adjustable connection to each other.

7. An emergency chain including an attaching member having pivotally connected jaws adapted to engage about an axle, a flexible draft element connected to one jaw and having sliding engagement with the other to hold the jaws together when the 55 draft element is subjected to strain, and a hook carried by the free end of the draft element.

In testimony whereof I affix my signature.
WILLIAM W. HUSTON. [L.S.]
